Primary Examiner — Leanne Was-Englehart*Assistant Examiner* — Yelizaveta Y Masalimova(74) *Attorney, Agent, or Firm* — DORSEY & WHITNEY
LLP(57) **CLAIM**

The ornamental design for a mid-sole traction device, as shown and described.

DESCRIPTION

FIG. 1 is a top perspective view of a mid-sole traction device, according to a first embodiment;

FIG. 2 is a bottom perspective view thereof;

FIG. 3 is a top plan view thereof;

FIG. 4 is a bottom plan view thereof;

FIG. 5 is a left elevational side view thereof;

FIG. 6 is a right elevational side view thereof;

FIG. 7 is a front elevational view thereof;

FIG. 8 is a rear elevational view thereof;

FIG. 9 is a top perspective view of a mid-sole traction device, according a second embodiment; and,

FIG. 10 is a bottom perspective view thereof.

The broken lines in the drawings depict portions of the mid-sole traction device that form no part of the claimed design.
